VOLUME CONTROL

John Hays Hammond, Jr., Gloucester, Mass.

Application September 7, 1929, Serial No. 390,879

5 Claims. (Cl. 250—20)

The object of this invention is to provide an improved method of controlling the magnitude of the output of a detector, repeater, or amplifier.

Another object of this invention is to provide a circuit by which radio signals, which are weak as received, due to fading, will produce output currents nearly as strong as the signals produced by the strong radio signals and thus tend to eliminate the effects of fading.

10 A further object of this invention is to provide for the automatic adjustment of a receiver circuit so that it may operate at maximum sensitivity for weak stations and reduced sensitivity for strong stations, thereby preventing over-loading 60 of the receiving and loud speaking equipment when receiving the latter stations.

20 A still further object of this invention is to provide a circuit which will bring in each station with approximately uniform intensity as the receiver is tuned throughout the broadcast band, regardless of the intensity of the actual radio 70 signals received.

An additional object is to provide an amplifier for use in cutting phonograph records whereby 25 the overloading of the last stages, which would cause blasting of the record, may be prevented.

These and further objects will become apparent from the following specification taken in connection with the accompanying drawings.

30 In accomplishing my invention, I use the currents in one part of the receiver circuit to determine the operating conditions in another part of the circuit. This general idea is subject to many variations. One method, for instance, is to 35 use the currents from some part of the circuits to determine or alter the bias of amplifier tubes. Another method, for example, includes the operation of the current in one part of the circuit to influence the detecting properties of a detector 40 device. Still another method is to utilize the currents in one part of a circuit to control the plate potential on the amplifier tubes.

Having thus briefly described my invention, attention is invited to the accompanying figures in 45 which:

Fig. 1 is a circuit wherein the radio frequency existing in the output of a thermionic detector is utilized to control the bias of an amplifier.

Fig. 2 is a circuit wherein the audio output of a 50 detector is used to control the grid bias on an amplifier device.

Fig. 3 is a circuit wherein the radio frequency component existing in the output of the detector is used to control the plate potential of an amplifier device.

Fig. 4 is a circuit wherein the radio frequency component existing in the output of the detector is used to control the detector action in the said detector.

Having thus briefly described the figures illustrating my invention, attention is invited more particularly to Fig. 1 which shows a regenerative detector circuit including the detector device 1 and its associated circuits. The input of said detector circuit includes the antenna 5, the condenser 6, and the inductance 7. The grid circuit is provided with the usual grid leak 9 and grid leak condenser 10 and the output of the detector device includes the tickler coil 11 variably disposed relative to the inductance 7, the output inductance 12 and the high potential source 13. Also included as a shunt circuit in the output of said detector device is the radio frequency bypass condenser 14, and the resistor 15, the latter of which acts as a coupling resistor and serves to impress a potential on the grid of the volume control tube 2. The primary 12 of the transformer 23 is inductively related to the secondary 22 which latter is included in the input circuit of the amplifier device 3. The input circuit of said 65 amplifier device includes also the coupling resistor 24, and the condenser 25. The output of the volume control tube 2 comprises the high potential source 21 and the grid leak 24 of the amplifier device 3. The amplifier device 3 has, in its 70 output circuit, the telephones 27 or any other reproducing device and the high potential source 28.

80 Referring now more particularly to Fig. 2, there is shown a similar circuit including a regenerative detector 1, a volume control tube 2, and amplifier tube 3. The output circuit of the detector device 1 includes the radio by-pass condenser 14, in series with the inductance 12 and across the said condenser there is disposed the inductance 17 which constitutes the primary of the transformer 19, 85 the secondary of which is adapted to supply the volume control tube 2. In other respects, this circuit is similar to that of Fig. 1, similar parts being designated by the same reference numerals.

100 Referring now more particularly to Fig. 3, there is shown a circuit which utilizes the volume control tube to vary the plate potential of the amplifier device. This circuit comprises the regenerative detector circuit including the detector 105 1 which circuit is similar to that shown in Figs. 1 and 2. The volume control tube 2 is adapted to be supplied by means of the resistor 15 included in the radio frequency by-pass circuit including also the radio frequency by-pass con-

denser 14, in a similar manner to that in which the volume control tube 2 is supplied in Fig. 1. The output of the regenerative detector is through the primary 12 of the transformer 23 the secondary 22 of which is adapted to supply the amplifier device 3 in the usual manner. A by-pass condenser may be provided across the winding 12 as shown. The plate circuit of the amplifier device 3 includes the output inductance 27, the resistor 26, and the high potential source 28. The resistor 26 is included also in the plate circuit of the volume control tube 2 in which circuit, but independent of the plate circuit of the amplifier 3, is included the high potential source 21. The transformer 30, the primary 27 of which is in the output circuit of the amplifier device 3, is adapted to supply the amplifier 4 through the secondary 29 in the usual and well known manner.

Referring now more particularly to Fig. 4, there is shown a detector device 1 having included in its input circuit the input inductance 7, the tuning device 8, the coupling resistor 9, and radio frequency by-pass condenser 10. The output of the detector device 1 includes the inductance 12, by-passed by a condenser, as shown, the inductance comprising the primary of the transformer 23, and the high potential source 13. There is provided a radio frequency by-pass circuit including the by-pass condenser 14 and the resistor 15 which latter is adapted to supply a potential to the grid of the volume control tube 2 through the grid leak 20 and grid leak condenser 16. The output circuit of the volume control device 2 includes the grid leak 9 of the detector device 1, and the plate potential of said device is supplied by source 13. The secondary 22 of the transformer 23 is adapted to supply the succeeding amplifier stages in the usual and well known manner.

Having thus described the circuits embodying my invention I will now describe their operation. In the case of the circuit shown in Fig. 1, the radio frequency current existing in and by-passed by the plate circuit of the detector 1 is impressed upon the grid circuit of the volume control tube 2, and the plate circuit of the volume control tube 2 includes the resistor 24, the latter of which is shunted by the condenser 25 as shown. The direct current in the plate circuit of the volume control tube 2 flowing through the resistor or grid leak 24 is made to depend upon the amount of voltage impressed across the resistor 15 in a well known manner. The resistor 24 is incorporated in the grid circuit of the amplifier tube 3. Adjustments are suitably made, such that on weak signals, the bias on 3 is such as to give maximum amplification. As the signals increase, the amount of radio frequency current by-passed from the plate of the detector tube increases, thereby increasing the direct plate current of tube 2, and consequently increasing the bias of tube 3. This produces a condition of operation of tube 3, giving less amplification so that strong signals from the transformer 23 do not produce relatively so great amplification as do the weak signals passing therethrough.

It is to be noted that in this case the input of the volume control tube 2 is radio frequency, while the current controlling the bias of amplifier tube 2 is of lower frequency than the audio currents, corresponding to a D. C. bias changing only the variation in the amount of radio signal strength at the rate of fading. Thus the true audio tones are inserted into the grid circuit of amplifier tube

3 by transformer 22, and frequencies inserted by the bias resistor 24 are of a lower order of magnitude, such that the output circuit of the amplifier will not respond to their presence.

In Fig. 2 the strength of the audio current in the plate circuit of the detector tube is made to control the bias in the grid circuit of the amplifier tube, as the radio frequency existing in the output circuit of the detector 1 is by-passed by the condenser 14 and is therefore not impressed upon the input of the volume control tube 2. The rectified output of the volume control tube 2, however, serves to vary the bias of the amplifier device 3 in the same manner as in Fig. 1.

In the broadcasting art, it is often the intent that there shall be changes in the volume of the signals, and this is accomplished by changing the amount of modulation. In order to have automatic control of volume which will operate from changes of the radio carrier intensity, but not from changes in the radio carrier modulation, it is desirable to provide the control stimulus from circuits carrying energy representative of the radio frequency, as is shown in Fig. 1. In a superheterodyne, the stimulus may be applied or supplied by the intermediate circuit, or the plate circuit of the second detector. If the controlling stimulus is supplied by the audio frequency as shown in Fig. 2, the automatic control will not be able to discriminate between the intentional changes, that is, change in volume of transmission, and to changes which it is desired to correct; and therefore in general Fig. 2 would usually not be preferable. In either of the forms shown in Figs. 1 and 2, the control tube may be used to control the bias on a number of amplifier circuits as, for example, in the superheterodyne, it may be used to control the bias of a large number of tubes producing considerably greater effect.

In Fig. 3 the circuit is arranged to control the amplification by variation of the plate voltage of the amplifier tubes. This is similar to Fig. 1, except that the tube 2 controls the applied plate voltage of the amplifier tube 3. For this purpose the tube 2 has in its input the resistor 15 in the radio frequency branch of the output circuit of tube 1 and has in its output circuit the resistor 26 which is common to the plate circuit of the amplifier tube 3, a suitable by-pass being provided across the resistance to the ground. Thus the D. C. plate voltage applied to the tube 3 is controlled by the plate current of the tube 2. With the tube 2 arranged to give increasing plate current with increasing signal, the plate voltage applied to the tube 3 diminishes and the amplification factor of this tube is therefore reduced.

In Fig. 4 the control tube is adapted to vary the detector characteristics of the detector 1. In this circuit the detector bias which is produced by the plate current of the volume control tube 2 flowing through the resistor 9, is varied in accordance with the radio frequency existing in the output of the detector 1, which is applied to the input of the volume control tube 2. This detector employs so-called plate rectification, and is biased normally to such a value that the increasing radio signals increase the direct current in its plate circuit. The volume control tube 2 is connected through the grid leak 20, and condenser 11 for radio excitation from the radio frequency by-pass circuit of the detector 1. This tube employs grid rectification, whereby increased radio voltage cuts down the bias of tube 2, reducing the plate current of this tube. As a result the current through the resistor 9 is diminished and the bias is dimin-

ished to a point where the detector acts as an amplifier with little or no detection.

The circuits embodying my invention have equal utility in the control of the current for use in the cutting of phonograph records wherein it is necessary to limit the amplitude of the cut to prevent blasting. The amplifier for the cutter may be arranged to have its last stages controlled in accordance with this invention, and thereby prevent the undesirable distortion in the record produced.

Having thus described my invention, it is to be understood that I am not to be limited to the specific embodiment shown and described for the purpose of illustration only, but by the scope of my invention as set forth in the appended claims.

I claim:

1. In a receiving system, a detector having an input and an output circuit, an amplifier coupled to the detector output and a source of signal modulated carrier energy coupled to said input, said detector acting upon said modulated carrier energy so that there exists in the detector output circuit separable high frequency and low frequency components of the signal modulated carrier energy, means for segregating and transforming said high frequency component into a direct current of an intensity varying in accordance with the intensity of the high frequency component and means for impressing said direct current upon a portion of said amplifier for controlling the amplification thereof in accordance with the intensity of the direct current.

2. In a receiving system a detector device comprising an input circuit coupled to a source of signal modulated carrier energy and an output circuit coupled to a vacuum tube amplifier, said detector device acting to render separable the carrier energy and the signal energy components of said signal modulated carrier energy, means for segregating and transforming a portion of one of said components into direct current of related intensity and means to control the static potential of the anode of said vacuum tube amplifier in accordance with the amplitude of the direct current.

3. In a signalling system, a detector device

comprising an input circuit coupled to a source of signal modulated carrier energy and an output circuit coupled to an amplifier system including at least one vacuum tube amplifier, said detector acting to render separable the carrier energy and the signal energy components of said signal modulated carrier energy, means for segregating and transforming a portion of said carrier energy component into direct current of related intensity and means to control the static potential of the anode of said vacuum tube amplifier in accordance with the amplitude of the direct current.

4. In amplifying systems and the like, a detector relay comprising an electronic tube provided with an input circuit and an output circuit, a source of signal modulated carrier energy coupled to said input circuit, an amplifier relay having input and output circuits, means for coupling the detector relay output circuit to the amplifier relay input circuit, a carrier energy by-pass path forming a part of said detector relay output circuit, means for controlling the amplification characteristics of said amplifier relay comprising an electronic tube having an input circuit including at least a portion of said carrier energy by-pass path and an output circuit including a source of current parallelly disposed with respect to the amplifier relay output circuit.

5. In amplifying systems or the like, a detector relay provided with input and output circuits, an amplifier coupled to the detector output circuit and a source of signal modulated carrier energy coupled to the detector input circuit, said detector relay acting upon the modulated carrier energy so that there exists in the detector relay output circuit separable carrier energy and signal energy components of the signal modulated carrier energy, means for segregating and transforming the carrier energy component into a direct current of an intensity varying in accordance with the intensity of the carrier energy component and means for impressing the direct current into a portion of said amplifier for controlling the amplification thereof in accordance with the intensity of the direct current.
